UNITED STATES PATENT OFFICE

OWEN T. WILKINSON, OF LOS ANGELES, CALIFORNIA, ASSIGNOR TO LOS ANGELES RUBBER STAMP CO., OF LOS ANGELES, CALIFORNIA, A CORPORATION OF CALIFORNIA

TAG-STAMPING MACHINE

Application filed April 17, 1928. Serial No. 270,663.

This invention relates to tag stamping machines, and the main object is to provide an improved means for stamping and cutting tags of uniform length from a continuous 5 strip of metal, and for consecutively numbering and stringing the tags in numerical order on a suitable wire or rod.

Another object is to provide an improved feeding mechanism for tag stamping presses 10 whereby successive portions of a continuous metal tape may be accurately measured and advanced to stamping position.

A further object is to provide means for accurately positioning the stamped and 15 punched portions of the metal strip for a cutting operation and for stringing the severed tags in numerical order on a suitable receiving device therefor.

An object is to provide an improved mechanism adapted for attachment to a standard 20 type of punch press so that sets of male and female consecutive numbering dies may be mounted on the bed and head of the press, respectively, in cooperative relation, together with means for feeding the continuous 25 strip of metal to stamping position, so that the successive portions of the strip may be stamped, punched, cut and strung on a suitable device at each operation of the head.

Still other objects will appear as the description progresses.

I have shown in the accompanying drawings an improved mechanism in preferred form for attaining the above objects, which 35 mechanism is subject to modification within the scope of the appended claims without departing from the spirit of my invention.

In said drawings:

Fig. 1 is a front elevation of a portion of a 40 standard type of power press with my improvements applied thereto;

Fig. 2 is an end elevation of the power spindle of the press showing an adjustable 45 means of connecting my mechanism with the driving means;

Fig. 3 is an end view of an adjustment device applied to the movable head of the press and adapted to cooperate with the device 50 shown in Fig. 2;

Fig. 4 is a plan of my improved mechanism as shown on line 4—4 of Fig. 1;

Fig. 5 is a sectional elevation of the feeding mechanism on line 5—5 of Fig. 1;

Fig. 6 is a transverse section of the numbering devices as seen on line 6—6 of Fig. 1; 55

Fig. 7 is a perspective view of a pivotally mounted pawl carrier typical of both sets of numbering devices;

Fig. 8 is a side elevation of a pawl employed in connection with both sets of numbering devices; 60

Fig. 9 is a perspective view of one of a pair of associated guides forming part of the tag stringing mechanism; 65

Fig. 10 is an end elevation of the tag stringing mechanism on line 10—10 of Fig. 1;

Fig. 11 is a fragmentary sectional plan of the same on line 11—11 of Fig. 10;

Fig. 12 is a fragmentary sectional elevation of the same on line 12—12 of Fig. 10; 70

Fig. 13 is a sectional plan of the same on line 13—13 of Fig. 10;

Fig. 14 is a view of a completed tag stamped and numbered. 75

Inasmuch as the press to which my improvements are applied is of standard type I have shown but fragments of the same in the drawings as represented by a suitable frame F on which a head H is reciprocably mounted and is adapted to be operated by means of the usual eccentric E. Said frame rotatably carries a spindle S which is journaled in the standards F', F' at its opposite ends. The eccentric E is operably connected with the head H by means of a connecting rod R. Frame F supports a bed B relative to which the head H is intermittently movable by means of the eccentric E. 80

Consecutive numbering devices N and N', 85 respectively, are provided on the head H and bed B which cooperate to stamp the numbers on the tags T as shown in Fig. 14. The numbering unit N is mounted on a suitable bracket n while the unit N' is mounted on supports n', n' attached to blocks b and b', positioned on the upper surface of the bed B. 90

A continuous strip of metal M is wound on a reel M' at the left end of the mechanism and is adapted to be fed longitudinally through 100

the machine by means of a feeding mechanism A, as shown in Fig. 1. The feeding mechanism is supported on a pair of transversely spaced members a and a' which are attached to the bed B and have bearings 1 and 2 oppositely formed thereon, respectively for rotatably supporting a spindle 3. Other bearings 4 and 5 are provided on the members a and a' for rotatably supporting spindles 6 and 7.

Spindle 3 carries a ratchet wheel 8 on its inner end and a gear 9 adjacent the inner side of the bearing 2 while the outer or front end of said spindle carries a drum 10 which is engaged on its periphery by a pair of brake shoes 11, 11. Said shoes are pivotally held at 12 on the member a and the upper ends thereof are adjustably connected by means of a bolt 13 for regulating the friction of the shoes on the drum.

Gear 9 is connected with a gear 14 on spindle 6 by means of an idler gear 15 which is rotatably held on the member a' by means of a shaft or stud 16. Spindle 6 carries a feed roller 17 which cooperates with a similar roller 18 on spindle 7 for feeding the metal tape M through the machine. Spindle 7 is driven by means of a gear 19 which meshes with gear 14 on spindle 6 and is resiliently mounted with respect to spindle 6 so as to permit the slight separation of the rollers 17 and 18 to permit the tape M to move therebetween.

To this end vertically movable bearings 20, 20 are mounted to slide in slots 21, 21 in the portions 4 and 5 of the members a and a' , respectively. Springs 22, 22 are held in compression between the bearings 20, 20 and caps 23, 23 attached to the upper ends of the portions 4 and 5 by means of bolts or cap screws as at 24. The ratchet 8 is intermittently operated by means of a connecting rod 25 which is pivotally connected at 26 with an arm 27 having an axis on the spindle 3. Said arm carries a pawl 28 which is pivoted at 29 to the arm 27 and is held in engagement with the ratchet 8 by means of a spring 30.

The upper end of connecting rod 25 is pivoted at 31 to a slide 32 which reciprocates in a groove 33 formed in a fixture 34 attached to the frame F, as shown in Fig. 3. Slide 32 in turn is connected with an eccentric 35 carried on the end of a spindle S by means of a rod 36, said rod being pivoted at 37 to slide 32 and at 38 to eccentric 35.

The pivot pin 38 adjustably and pivotally connects the rod 36 with the eccentric 35, a groove 39 being provided therein in which the pin slides so as to adjust the throw of the rod 36 to conform to the required length of metal tape M which is adapted to be fed at each operation of the machine to the stamping press.

The reel M' which carries the metal tape M is rotatably mounted on a bolt 40 which

spans a pair of standards 41, 41 carried on the ends of a pair of brackets 42, 42 extended from the bed B of the machine. The standards 41 may be extended so as to accommodate a plurality of the reels M', if desired, as shown in Fig. 1. Thus the tape M is fed from the reel M' between the members a and a' and beneath a plate 43 suitably attached to said members. From thence the tape is fed between the rollers 17 and 18 which frictionally engage the tape and move the same into the machine and between the stamping dies N and N'.

When the forward end of the tape M is properly positioned for a stamping operation, as shown in Fig. 4, at the beginning of a series of consecutive stamping and numbering operations, the initial downward thrust of the head H will move the stamping and numbering dies N into cooperative engagement with the strip M, which together with the dies N' will imprint upon a portion of the tape the beginning of a series of consecutive numbers. At each movement of the head H similar numbering and stamping operations will be effected and the successive portions of the tape T will be consecutively numbered.

Head H also has a punch 44 held in the member n in registration with an aperture 45 in the member n' which serves to punch a hole as at 46 in the inner end of each successive portion of the tape when the head H is moved downwardly. At the same time the metal is stamped and punched, the tags T are cut from the strip of tape by means of a pair of cooperating cutters C and C' which are attached respectively to the head H and to a block b' held on the bed B, as shown in Fig. 12. The cutter C' has a pair of oppositely formed arcuate cutting edges 47 and 48 formed thereon which cooperate with similar edges 47' and 48' on the cutter C of the head for cutting the tape M at adjacent ends. The tape M is fed at each operation of the machine and prior to the downward movement of head H so that the inner end of the completed tag T will engage the cutting edge 48 and the previously punched hole 46 will register with a vertical stringing rod 49 which is concentrically positioned relative to the edge 48. The succeeding movement of head H will effect the cooperation of the cutters C and C' to cut the tape M at two separate and slightly spaced points, as shown in Fig. 4, coincident with the cutting edges 47 and 48. This operation, each time, leaves the inner end of the completed tag in such a position that it will readily drop on to the tapered end 50 of the rod 49, while the scrap pieces, as at 51, will be ejected from the machine by suitable means not essential to this invention.

By reference to Fig. 12 it will be observed that the cutter C has a plunger which is provided with a head 52 corresponding in form

to and slidably in the cutter C. This head is urged downwardly from the cutter C by means of a compression spring 53 on the stem 54 thereof. The cutter C has a recess 55 to receive a head 52 and the head H has a bore 57 to slidably receive the stem 54 of the plunger, while the head also has a counterbore 56 to receive an enlargement 58 on the plunger, in which the spring 53 is held. Cutter C' has a pair of upstanding lugs 60, 60 which engage a recessed portion 52' of head 52.

A plunger 61 is also provided in the block b' with a head 62 and a stem 63. Said head operates in a recess 64 and is urged upwardly by a spring 65 held in compression between the head 62 and the bottom of the recess 64. The stem 63 seats in a bore 65 and is moved downwardly during a cutting operation. Thus the metal M is held over the head 62 prior to and during a cutting operation and prevents a crinkling or bending of the end of a tag. The tape M is fed through a slot 66 in block b' beneath a plate 66'.

It will be noted that the block b' has a vertical groove 67 which registers with and extends downwardly from the cutting edge 48 of cutter C' and that the rod 49 is concentrically held in said groove, so that the successive tags T will be strung on the rod in consecutive order. The top of block b' has a pair of transversely and oppositely movable bars 68 and 69 which underlie the cutting edge 48 and normally overlie the upper end of the groove 67 in said block, so as to provide a seat for the inner end of the tags T. These bars are adapted to be retracted at the completion of each stamping and cutting operation so as to permit the tags to drop on to the rod 49 in succession and are actuated by means of a pair of similar bars 70 and 71 which are rigidly attached to and depend from a portion 72 of the head H by means of feet 73 and 74, respectively. The lower ends of said bars carry pins 75 and 76 which are adapted to engage and depress portions 77 and 78 of bell cranks D and D' which are pivoted to the block b' at points 79 and 80, respectively. Vertical arms 81 and 82 on said bell cranks have reduced upper end portions 83 and 84 respectively which seat in corresponding apertures in the outer ends of the bars 68 and 69. Thus when the head H moves downwardly the pins 75 and 76 engage the arms 77 and 78 of bell cranks D and D' and move them downwardly against the tension of springs 85 and 86, while the arms 81 and 82 are correspondingly moved outwardly together with the bars 68 and 69. The operation of bars 68 and 69 are so timed that they will retract only upon the completion of a cutting operation and will be restored upon the initial upward movement of the head.

When the tape M is positioned, as in Fig. 4, over the cutter C' and rod 49 and bars

68 and 69, the initial movement of the head H downwardly will engage a tubular plunger 87 with the tape M and effect the retraction upwardly of the plunger into a recess 88 in the cutter base C, while its stem 89 will slide in a bore 90 and an enlargement 91 thereon will move in a counterbore 92 against the tension of a spring 93 held in said counterbore and tending to urge the plunger outwardly. At the completion of the cutting operation the tubular plunger 87 will force the completed tag downwardly on to the rod 49 and the plunger will encompass said rod for a substantial distance prior to the beginning of the upstroke of the head, so as to insure the deposit of the tags on the rod 49 at each operation.

The numbering devices N and N' are standard equipment, or rather of well known type and embody progressive numbering dies in the form of wheels 94, 94 etc., arranged in ascending order by units, tens, hundreds, thousands, etc. The stamping segments 95 are arranged at regular intervals on the peripheries of the wheels and each wheel has a ratchet 96 with ten notches 97 therein adapted to be engaged successively by detents 98 which are pivotally mounted as at 99 on portions 100 and are resiliently held in engagement with the ratchets by means of springs 101, for preventing the operation of the wheels in other than a single direction. The wheels 94 are moved forwardly, step by step, by means of a composite pawl 102 which has a plurality of spaced arms 103, 103 etc. of different length. The longest of these arms registers with and is adapted to operate the units counter wheel, the next to the longest operates the tens wheel, etc. so that the operation of the wheels will progress from units to tens, from tens to hundreds, etc. for maintaining a proper sequence in a numbering operation. Needless to say the units N and N' are synchronized so that the same numbers will be in operative position on both sets of dies at each operation of the press.

The pawl 102 is pivotally held on a carrier 104 of U shape, the arms 105 and 106 are pivoted on the shaft as at 107 of the numbering wheels. The pawl is held resiliently in engagement with the ratchets by means of a suitable tension spring 108. The units N and N' are similarly operated to a like extent at each operation of the head H by means of bars 109 and 110 which are pivotally and slidably connected with the pawl carriers 104 of the units N and N', respectively. Said bars have elongated slots 111 which receive pins 112 projecting from one of the arms 105 or 106 of the pawl carriers 104, as shown in Fig. 6. On the downward movement of the head H the bar 109 will initially slide on the pin 112 until the pin reaches the bottom of slot 111. The bar which is pivotally attached at its lower end to a por-

- tion of the fixture n' will effect the movement of the pawl carrier and pawl for a sufficient distance to advance the numbering wheels one tenth of a revolution. Likewise the bar 110 being similarly connected with the unit 5 N' and pivoted at its upper end to the fixture n , will operate the unit N' to conform to the operation of unit N , by the same means and at the same time.
- 10 Reverting to the bars 68 and 69, it will be noted in Fig. 9 that the upper portion of block b' has a pair of fixtures 114 and 115 which are attached to block b' by suitable means on opposite sides of the groove 67 for directly supporting said bars for operation. 15 The upper ends of said fixtures have grooves 116 therein in which the bars 68 and 69 are adapted to slide and recesses 117 are provided in extensions 118 for the reception of the 20 arms 81 and 82 of the bell cranks D and D' . In operation, the metal tape M is fed intermittently by means of the rollers 17 and 18 from the reel M' into position between the 25 numbering dies N and N' , the tape being held against lateral movement beneath the plates 43, 43' and 66', with the outer end of the tape extended beyond the cutting edge 47 of the cutter C' at the beginning of a series of 30 operations.
- 30 The feeding of the tape as described is accomplished by means of the upward movement of the head H while the numbering dies are correspondingly actuated on either the up stroke or the down stroke of the head for 35 the ensuing numbering and stamping operation. The first operation of a series with a given strip of material punches the holes 46 in the tags T and the outer end of the tape is trimmed simultaneously therewith by the 40 cutters C and C' at the cutting edge 47. At the subsequent operations of a series the completed tag T is severed from the strip M and the succeeding tag is punched and numbered. Thus the tags are punched and numbered before they are cut from the tape. 45
- 45 The female die C is on the head H instead of the bed B as is usual in punch presses and the plunger head 52 of the upper die engages the metal tape M near the completion 50 of the down stroke of the die C and before the dies C and C' are moved into operative engagement. Thus the head 52 serves to resiliently hold the tape M in cutting position. As die C moves further in the direction of die C' the head 52 is retracted against the tension of spring 53. At the completion 55 of the cutting operation the lugs 60, 60 on die C' engage the recessed portion 52' on head 52 for a further distance equal approximate- 60 ly to the thickness of the tape M. When the die C is retracted upwardly the tension of spring 53 serves to eject the waste portions of the tape, while the completed tags T are fed by means of the plunger 87 on to the 65 stringing rod 49, the sliding bars 68 and 69

having just previously been retracted outwardly. Succeeding operations are accomplished in like manner in rapid succession and the tags are consecutively numbered.

When the tape M on the operative reel M' 70 is exhausted the machine may be stopped while another reel is substituted for the previous reel.

The tape M from the reel is threaded by hand through the guide plate 43 and into position of engagement with the rollers 17 and 18, whereupon the feed rollers are turned by hand until the tape is properly positioned between the stamping dies N and N' . Accordingly the first ensuing stamping operation 80 will completely stamp, number and form the first of a series of tags and the surplus material at the discharge end of the machine will be cut therefrom.

Such a mechanism as I have disclosed here- 85 in is valuable in the production of large quantities of consecutively numbered tags in that it provides automatic means for feeding, numbering, forming, counting, cutting and stringing the tags, whereas in other devices many 90 of these operations have been accomplished manually and at much slower speeds than is possible with my improvements.

What I claim is:—

1. A machine of the character described 95 comprising relatively movable and correspondingly operative consecutive numbering dies, means for feeding successive portions of a continuous strip of metal into stamping position between said dies, means for cutting the stamped portions from said strip, means for punching a hole in each stamped and cut portion of the strip and a stringing rod arranged to project thru the holes of the successive stamped and cut portions for collecting and holding stamped and cut portions in consecutive order.

2. A tag stamping machine comprising a press, stamping dies thereon, means for automatically feeding successive portions of a 110 continuous strip of material to and from position between said dies, and means for simultaneously punching, stamping and cutting each successive portion of the strip to form a tag, and means for collecting the tags formed 115 from said strip in consecutive order.

3. A tag stamping machine comprising a press, stamping dies thereon, means for feeding successive portions of a strip of material to and from position between said dies, means 120 for adjusting the feeding mechanism for varying the length of the portions so fed to the dies, means for punching apertures in corresponding positions on the successive portions of the strip and means engaging said 125 apertures for collecting the completed tags in consecutive order.

4. A tag stamping machine comprising a press, relatively movable and stationary dies thereon, means for feeding tag forming ma- 130

- terial to and from position between said dies, cutters associated with said dies, one of said cutters provided with a yieldable head adapted to engage the stamped tags prior to the 5 cutting operations, and means for collecting said tags in consecutive order.
5. A tag stamping machine comprising a press, relatively movable and stationary dies thereon, means for feeding successive portions of a strip of material to and from position between said dies, means for cutting the stamped tags from said strip, a tag receiving member, means normally preventing the deposit of and retractable to permit the 10 deposit of the tags thereon, and yieldable means associated with the movable die and operable while said last mentioned means is retracted, for effecting the deposit of the tags in consecutive order on said receiving 15 member.
15. A tag stamping machine comprising a press, relatively movable and stationary stamping dies thereon for consecutively numbering successive tags, means for feeding successive portions of an elongated strip of material to and from position between said dies, a yieldable member for engagement with the stamped tags during a cutting operation, cutters for separating the tags, a collecting 20 member, and yieldable means cooperating with said collecting member and for engagement with said tags for depositing the same in consecutive order on the collecting member.
25. 7. A tag stamping machine comprising a frame, a bed and a relatively movable head on said frame, stamping dies mounted respectively on said bed and on said head, means for feeding successive portions of a strip of material to and from position between said dies, means for intermittently moving said head for effecting the cooperation of the dies in successive stamping operations, means for cutting the completed tags 30 from said strip of material, and means for collecting said tags on a common receiving member in the order in which they are stamped.
35. 8. A tag stamping machine comprising a press, stamping dies thereon, one of said dies being reciprocable relative to the other die, means for feeding a strip of metal into and from position between said dies, means for cutting the strip to form tags, means for receiving the completed tags in consecutive order, means associated with the reciprocable die for depositing the successive tags on said receiving means.
40. 9. A tag stamping machine comprising a press, relatively movable and stationary dies thereon for simultaneously numbering, and punching apertures in and cutting, each successive portion to form consecutively numbered tags, means for progressively feeding a strip of metal to and from position between 45

tion on said press, and means operative subsequent to the consecutive numbering and perforating mechanisms for cutting the tags from said strip of material and for collecting the same in consecutive order.

17. A tag stamping machine comprising a press, a fixed die and a relatively movable die thereon, means for intermittently feeding successive portions of a strip of material into and from position between said dies, means for consecutively numbering and perforating successive portions of said strip of material and for forming the outer ends of said portions at given operations of the machine, and means for cutting said strip of material at the inner ends of said tag forming portions at successive operations of the machine.

18. A tag stamping machine as characterized in claim 17, and means for collecting said tags in consecutive order subsequent to the severing operation.

OWEN T. WILKINSON.
